SAFETY DEVICE FOR WELL TUBING

Delbert S. Bradley, Chase, Kans.

Application February 28, 1939, Serial No. 259,071

7 Claims. (Cl. 166—1)

This invention relates to a safety device for a well tubing and has for the primary object the provision of a device of this character which will automatically prevent falling of well tubing in a well during the time of handling of said tubing or should the tubing become accidentally detached by any cause and also will act to guide the tubing in the casing of the well while said tubing is being raised or lowered to prevent the tubing from cocking in the well.

With these and other objects in view, the invention consists in certain novel features of construction, combination and arrangement of parts to be hereinafter more fully described and claimed.

For a complete understanding of my invention, reference is to be had to the following description and accompanying drawings, in which

Figure 1 is a fragmentary vertical sectional view illustrating a well having therein the usual casing and tubing to which the present invention is adapted.

Figure 2 is an enlarged vertical sectional view showing the safety device in the act of supporting the tubing.

Figure 3 is a sectional view taken on the line 3—3 of Figure 2.

Figure 4 is a sectional view taken on the line 4—4 of Figure 2.

Figure 5 is a vertical sectional view showing the complete safety device detached from the tubing.

Figure 6 is a perspective view illustrating an expandible member.

Figure 7 is a fragmentary vertical sectional view illustrating a modification of the present invention.

Referring in detail to the drawings, the numeral 5 indicates a well in which is located the usual casing 6 that extends to the bottom of the well. Also shown in the well is tubing 7 and to which the present invention is adapted for the purpose of guiding the movement of the tubing in the casing to prevent cocking of the tubing during either the time of raising or lowering of said tubing and also to automatically stop the fall of the tubing should the latter become free or detached during the handling thereof.

A tube 8 of the same diameter as the tubing 7 has its upper and lower ends externally screw threaded, as shown at 9. The upper end of the tube 8 is adapted to be coupled either onto the tubing 7 or a pump barrel carried by the tubing 7. The tube 8 has its upper end closed by a disc 10 welded therein and said tube 8 below the disc

is provided with a series of slots 11 to permit the flow of liquid of the well to pass up through the tube and escape therefrom by way of the slots 11.

A valve cage 12 is threaded on the lower end of the tube 8 and has therein a valve seat 13 and coacting with said seat is a valve element 14 connected to a stem 15 slidably supported in a spider 16 located above the valve seat while the valve element 14 is located below the seat. The valve element 14 becomes unseated by gravity and is preferably of conical shape having its apex disposed uppermost and the seat 13 is shaped to match the contour of the valve element.

A sleeve 17 is shrunk or otherwise secured on the tube 8 below the slots 11 and above the valve cage 12 and has its upper end externally screw threaded on which is threaded an annular member 18 carrying a plurality of tie bolts 19 which support at the lower end thereof an annular member 20 slideable on the sleeve 17.

An expansible member 21 of cylindrical shape is mounted on the tie bolts between the annular members 18 and 20 and is preferably constructed from rubber. The sleeve 17 and the tube 8 are provided with aligned openings 22 located slightly above the annular member 20 when the latter is in its lowermost position so that the openings 22 will be covered by the expansible member 21.

Under normal operation the flow of liquid of the well may be through the tube 8 due to the fact that the valve 14 is opened by gravity and escapes from the tube by way of the slots 11. Thus it will be seen that the tube normally will not interfere with the flow of fluid in the well. However, should the well tubing become free and start to fall the valve 14 is immediately closed by the movement of the valve cage through the fluid of the well and as the external diameter of the expansible member 21 is only slightly less than the internal diameter of the well casing the pressure of the fluid on the lower annular member 12 due to the falling of the tube 8 with the well tubing causes the annular member to slide upwardly compressing the expansible member 21 against the annular member 18, bringing about a bulging of the member 21 so that it tightly fits the well casing and becomes wedged therewith, consequently preventing the falling of the well tubing and the present invention to the bottom of the well with any great force that would cause damage either to the well or well tubing. As the annular member 20 slides upwardly under the pressure of the fluid in the well during the falling of the well tubing the ports or openings 22 become uncovered, allowing a small amount of

fluid to pass into the tube 8 and escape therefrom by way of the slots, the purpose of which is to allow the device in entirety to slowly descend in the well.

5. Should the well be of the type furnishing oil and gas, it will be preferable to provide hollow tie bolts 24 in lieu of the solid tie bolts 19 and connected to the upper ends of the hollow tie bolts 24 are pop-off valves 25 of conventional 10 construction. Should the falling of the device in the well occur in a gradual manner while the well is developing gas rapidly there is a possible chance that the pressure of the gas will exceed a danger mark sufficient to damage the well casing 15 and to prevent this from occurring the pop-valves 25 will permit the escape of gas when the pressure exceeds a predetermined amount.

It is believed that the foregoing description, when taken in connection with the drawings 20 will fully set forth the construction and advantages of this invention to those skilled in the art to which such a device relates, so that further detailed description will not be required.

What is claimed is:

25. 1. In a device of the character set forth, a tube adapted for connection with a well tubing, a valve in said tube and normally open during the non-movement of the tube in relation to the liquid of the well to permit flow of the liquid 30 through said tube, and means carried by said tube to act as a guide for the well tubing during its movement relative to a well casing prior to entering the liquid of the well and adapted to expand against the well casing by a movement 35 of the tube through the liquid of the well for checking the descent of the tubing should it become free in the well.
2. In a device of the character set forth, a tube adapted for connection with a well tubing, 40 a valve in said tube and normally open during the non-movement of the tube in relation to the liquid of the well to permit flow of the liquid through said tube, and an expandible member on said tube and having one end anchored on 45 the tube and its other end free to slide relative to the tube by pressure of the liquid of the well thereagainst for wedging with the well casing to check the downward movement of the tubing should the latter become freed.
50. 3. In a device of the character set forth, a tube having one end closed and provided with slots adjacent to said end and having the latter-named end coupled to a well tubing, a gravity actuated valve carried by the other end of the 55 tube and normally open and adapted to close by the movement of the tube rapidly through liquid of the well, a sleeve mounted on the tube below the slots and above said valve, and an expandible member carried by said sleeve.
60. 4. In a device of the character set forth, a tube having one end closed and provided with slots adjacent to said end and having the latter-

named end coupled to a well tubing, a gravity actuated valve carried by the other end of the tube and normally open and adapted to close by the movement of the tube rapidly through liquid of the well, a sleeve mounted on the tube 5 below the slots and above said valve, an annular member secured on one end of the sleeve, a second annular member slidable on said sleeve, and an expandible member supported by said annular members on the sleeve.

5. In a device of the character set forth, a tube having one end closed and provided with slots adjacent to said end and having the latter-named end coupled to a well tubing, a gravity actuated valve carried by the other end of the 15 tube and normally open and adapted to close by the movement of the tube rapidly through liquid of the well, a sleeve mounted on the tube below the slots and above said valve, an annular member secured on one end of the sleeve, a second 20 annular member slidable on said sleeve, an expandible member supported by said annular members on the sleeve, tie bolts extending through the annular members and the expandible member.

6. In a device of the character set forth, a tube having one end closed and provided with slots adjacent to said end and having the latter-named end coupled to a well tubing, a gravity actuated valve carried by the other end of the 30 tube and normally open and adapted to close by the movement of the tube rapidly through liquid of the well, a sleeve mounted on the tube below the slots and above said valve, an annular member secured on one end of the sleeve, a second annular member slidable on said sleeve, an expandible member supported by said annular members on the sleeve, tie bolts extending 35 through the annular members and the expandible member, said sleeve and tube having aligned openings normally covered by the expandible member.

7. In a device of the character set forth, a tube having one end closed and provided with slots adjacent to said end and having the latter-named 45 end coupled to a well tubing, a gravity actuated valve carried by the other end of the tube and normally open and adapted to close by the movement of the tube rapidly through liquid of the well, a sleeve mounted on the tube below the slots and above said valve, an annular member secured on one end of the sleeve, a second annular member slidable on said sleeve, an expandible member supported by said annular members on the sleeve, tie bolts extending 50 through the annular members and the expandible member, said sleeve and tube having aligned openings normally covered by the expandible member, said tie bolts being of hollow formation, and pop-off valves connected to the upper ends 60 of said tie bolts.

DELBERT S. BRADLEY.
